CLAIM

The ornamental design for a wrestling headgear with attachable hook, as shown and described.

DESCRIPTION

FIG. 1 is a perspective view of a wrestling headgear with attachable hook showing my new design in a position of use and the hook in a detached state;

FIG. 2 shows a front view of the wrestling headgear with attachable hook in the detached state;

FIG. 3 shows a back view of the wrestling headgear with attachable hook in the detached state;

FIG. 4 shows a left view of the wrestling headgear with attachable hook in an attached state;

FIG. 5 shows a right view of the wrestling headgear with attachable hook in the attached state;

FIG. 6 shows a top view of the wrestling headgear with attachable hook in the detached state; and,

FIG. 7 shows a bottom view of the wrestling headgear with attachable hook in the detached state.

The broken lines in the FIGS. 1-3 and 6 depicting a wearer's head represents environmental subject matter that forms no part of the claimed design. The broken lines in the FIGS. 1 to 7 depicting a mouth guard represents environmental subject matter that forms no part of the claimed design.

The lines of stitching on the wrestling headgear form a part of the claimed design.

1 Claim, 7 Drawing Sheets
